HEAT DISSIPATING MEANS FOR ELECTRON
MICROSCOPES
Perry C. Smith, Moorestown, N. J., assignor to
Radio Corporation of America, a corporation of
Delaware
Application December 30, 1944, Serial No. 570,662
7 Claims. (Cl. 250—49.5)

1 The present invention relates to electron microscopes and more particularly to the dissipation of heat from critical parts.

In the operation of electron microscopes as at present constructed the heat developed by electronic bombardment and infra-red radiation causes the different metals of the anode and cathode assemblies to expand at different rates so that in the operation of the microscope the image drifts over the fluorescent screen and interferes with accurate observation and clear cut photographic reproductions.

Some of the objects of the present invention are to provide an improved image projection; to provide means wherein provision is made for dissipating heat which ordinarily impairs the projection of the specimen image; to provide means to prevent drifting of the specimen image while under observation or during photographing of the same; to provide a novel anode structure wherein heat usually detrimental to object viewing or picture taking is no longer effective; and to provide other improvements as will hereinafter appear.

In the accompanying drawings, Fig. 1 represents a fragmentary section on the longitudinal axis of a microscope column showing the interior of the electron gun in association with the object or specimen chamber, said parts embodying one form of the present invention; Fig. 2 represents a sectional enlarged detail on line 2—2 of Fig. 1; and Fig. 3 represents a perspective of the heat reflecting plate.

Referring to the drawings, one form of the present invention is shown as assembled upon the column of an electron microscope, the parts necessary for an understanding of the invention being the electron gun 10, and the object chamber unit 11. The electron gun 10 is carried by a housing 12 attached to an annular base 13 adjustably mounted upon the unit 11, and encircling the axially disposed cathode 14 which is mounted in the apertured tube 15 and electrically insulated from the main or central support of the gun. External connections are provided by leads 16 which extend through glass seals 17 at the rear end of the gun assembly.

In order to dissipate the heat developed by the electronic bombardment and infra-red radiation, the anode 18 is made of a metal having high heat conductivity, preferably copper, and is of relatively heavy thick wall construction. As shown, the anode 18 is cup shaped and provided with the usual focussing aperture 20, which latter in assembled condition is coaxial with the axis of

2 the microscope column. The annular side wall of the anode 18 has a snug fit within the complementary hole provided in the casting of the object chamber unit 11, while its outer rim is crimped as shown at 21 into a recess provided in the face of the unit 11. In the present instance the anode wall is abnormally long to form a skirt extension presenting a large contact area against the unit 11 to carry off rapidly heat from the anode, and is spaced from and coaxially encircles the cathode elements of the gun. Radially disposed ports 22 form communication with the chamber of the unit 11 to permit vacuum pumping to take place.

15 To enhance the heat absorbing properties of the anode, its surface is finished preferably with some black material, such as carbon, graphite, aquadag or a black oxidization product as indicated at 23.

20 As a further means of preventing heat from reaching the specimen stage 24, a heat reflecting plate 25 having a highly polished face 26 is suitably mounted between the stage 24 and the anode 18, being spaced from the latter and of a size **25** to bring all parts of the face 26 into juxtaposed relation to the stage end of the anode 18. Thus, a great portion of the heat radiated from the anode towards the stage is thus reflected back to the anode for dissipation as noted above.

30 From the foregoing it will now be apparent that a novel heat absorbing means has been devised whereby the temperature of the specimen stage, specimen holder, and adjacent parts is kept sufficiently low as to prevent metals having different coefficients of expansion and contraction from being affected. In the absence of the assembly of the present invention the high temperature of the radiated heat causes these metals to expand and contract unequally so that the **35** stage is constantly in slow motion, and so seriously interferes with the production of sharp photographic images.

I claim as my invention:

1. In an electron microscope, a unit forming an object chamber, a stage in said chamber, an electron gun including cathode and anode electrodes arranged to project an electron beam into said object chamber, and means associated with said anode to so dissipate the heat developed by electronic bombardment and infra-red radiation as to reduce the temperature of heat transmitted to said stage, below the point where unequal expansion and contraction of metal parts within said object chamber takes place.
- 50 2. In an electron microscope, a unit forming

an object chamber, a stage in said chamber, and an electron gun including cathode and anode electrodes arranged to project an electron beam into said object chamber, said anode being made of copper and mounted in surface contact with said object chamber unit, whereby said stage is subject to low temperature heat.

3. In an electron microscope, a unit forming an object chamber, a stage in said chamber, an electron gun including cathode and anode electrodes arranged to project an electron beam into said object chamber, said anode being made of copper and mounted in surface contact with said object chamber unit, and a reflector plate between said stage and anode to reflect heat away from said stage.

4. In an electron microscope, a unit forming an object chamber, a stage in said chamber, an electron gun including cathode and anode electrodes arranged to project an electron beam into said object chamber, said anode being made of copper and mounted in surface contact with said object chamber unit, and a black coating on the surface of said anode.

5. In an electron microscope, a unit forming an object chamber, a stage in said chamber, an electron gun including cathode and anode electrodes arranged to project an electron beam into said object chamber, and means including a reflector plate between said stage and anode to so dissipate the heat developed by electronic bombardment and infra-red radiation as to reduce the temperature of heat transmitted to said stage, below the point where unequal expansion and contraction of metal parts within said object chamber takes place.

6. In an electron microscope, a unit forming an object chamber, a stage in said chamber, an electron gun including cathode and anode electrodes arranged to project an electron beam into said object chamber, and means including a black coating on said anode to so dissipate the heat developed by electronic bombardment and infra-red radiation as to reduce the temperature of heat transmitted to said stage below the point where unequal expansion and contraction of metal parts within said object chamber takes place.

7. In an electron microscope, an electron gun including a cathode electrode and an anode electrode, said anode having through ports and an aperture coaxially located with respect to said gun, a unit as a part of the microscope column and having an end opening, and means for attaching said gun to said unit, said anode being of heat conducting material and having a skirt extension fitting said unit opening and having a length substantially equal to the length of said opening to provide a maximum heat dissipating area.
